ALL-CAST DIPPER

Paul V. Larsen and Elmer L. Larson, Portland, Oreg., assignors to Electric Steel Foundry Company, Portland, Oreg., a corporation of Oregon

Application September 16, 1957, Serial No. 684,217

5 Claims. (Cl. 214—145)

This invention relates to an all cast dipper and method of forming the same. The invention is particularly useful in the forming of a power shovel dipper.

Power shovel dippers, because of their huge size and weight and because of their heavy use and wear resulting in shortened life of the dipper, have long presented a problem. If parts of the structure could be formed in separate castings and then readily united in a durable dipper structure, great expense would be saved and the cost of the dipper could be substantially reduced. Castings have heretofore been formed with lap joints which are then riveted or lap-welded, but such procedure requires that the castings meet close specifications and have very little variations. Butt-welding procedures have not been followed and have not been considered feasible because of the stresses imposed upon the dipper, the stresses being in different directions in the operation of the tool, and because of other difficulties having to do with the pre-arranging of the parts for welding, etc.

We have discovered that an all cast dipper can be formed in a very inexpensive manner while employing butt-welding and while at the same time providing a completed structure which is buttressed against the stresses operating in different directions so as to form an effective dipper tool. By the new method, a dipper can be formed from cast parts which allow great variation in the parts while at the same time enabling assembly and union to be effected with a minimum of labor and in a modicum of time.

An object of the present invention is to provide an all-cast dipper formed of different parts equipped with companion means for uniting them readily and maintaining them in proper position for butt-welding, the butt-welding being accomplished in such a manner as to provide a structure which is effective against the unusual stresses from the many directions to which a dipper is subjected. Another object is to provide a dipper structure in which the parts are united by butt-welding along curved or arcuate lines which buttress the points of union against the heavy stresses to which they are subjected. Yet another object is to provide a method and means whereby cast parts may be readily brought together and assembled with a minimum of labor so that butt-welding can thereafter unite the parts into a unitary dipper structure. Other specific objects and advantages will appear as the specification proceeds.

The invention is shown, in an illustrative embodiment, by the accompanying drawings, in which:

Figure 1 is a side view in elevation of an allcast dipper embodying our invention; Fig. 2, a broken top view in elevation of the dipper; Fig. 3, a side elevational view of the component castings arranged in spaced-apart relation prior to their union; Fig. 4, a rear view in elevation; Fig. 5, a broken front view in elevation; Fig. 6, an enlarged broken detail view showing the method of connecting the lip, front and side castings; Fig. 7, a broken detail sectional view showing the method of connecting the lip

2

casting to the front casting; Fig. 8, a view similar to Fig. 7 showing the fit-up bolt removed; Fig. 9, a broken detail sectional view showing the side casting united to the lip casting and providing V-recesses for receiving the welding metal; Fig. 10, a view similar to Fig. 9, showing the welding metal in place; Fig. 11, a view similar to Fig. 10, showing the removal of the fit-up bolt; and Fig. 12, a detail sectional view showing the connecting of the bail-ear to the back casting.

10 In the illustration given in Fig. 3, A designates a side casting, B designates a lip casting equipped with the usual adapter and points, C designates a front casting having a heel portion C', D designates a back casting, and E designates a bail ear which is to be connected to the side and back castings. The separate castings are united in one unitary dipper structure, as shown in Fig. 1. A door F is mounted upon a pivot 19 carried by the hinge members 11 forming a part of the back D.

In the practice of our invention, we form the separate 20 castings with beveled edge portions adapted to form, with beveled edge portions of companion castings, a V-shaped recess adapted to receive the welding metal, and along such edge portions we form spaced ear lugs which are apertured to receive fit-up bolts for the attachment of 25 the castings to each other. By providing the edge portions of the ear lugs with beveled edges, we find that arcuate lines of welding are provided which enable the integrated casting to withstand the unusual stresses of a dipper. Further, we employ inclined lines of butt-welding 30 between the important lip, front and side castings so as to provide an unusually sturdy union between these parts effective for withstanding the unusual stresses to which the dipper is subjected, while at the same time providing for greater area in the lip casting and the heel portion of 35 the front casting where wear is the greatest.

Referring more specifically to Figs. 3 and 6, the lip casting B is equipped at the side opposite the points 12 with a beveled edge 13 merging with an ear lug 14. The ear lug 14 is provided with a fit-up hole 15.

40 The adjacent side A is provided with a beveled edge 16 and with three lugs 17, 18 and 19, each being provided with a fit-up hole 15. Each of the ear lugs 17, 18 and 19 is provided with a beveled edge about its curved periphery which is a continuation of the beveled edge 16 of the 45 casting.

The front casting C has a pair of ear lugs 20 and 21, the lug 20 mating with the ear lug 19 of casting A, and the ear lug 21 mating with the ear lug 18 of casting A. The ear lugs 20 and 21 also have fit-up holes 15. The 50 upper edge portion of the front casting C is provided with a beveled edge 22 which forms a V-recess with the lower beveled side 13 of lip casting B. A beveled edge 23 extends between the ear lugs 20 and 21 of casting C.

The ear lugs 14 of lip casting B and the ear lugs 20 and 55 21 of the front casting C also have beveled edges, but these beveled edges are not shown in the structure shown in Fig. 3. The edges are indicated by dotted lines in Fig. 6. The edge bevel 13 of casting B extending around the ear lug 14 is shown clearly in Figs. 9, 10 and 11. Also 60 illustrated in Figs. 9, 10 and 11 is the fact that the ear lugs are formed along their inner sides with flat faces which lie against each other while at the same time providing V-recesses 24 and 25 between the companion parts and into which the welding metal 26 is later placed.

65 Referring again to Fig. 3, each side casting A is provided at its rear with a beveled edge 27 which extends also around the two spaced ear lugs 28 and 29. The back casting D has similarly a beveled edge 30 which extends around an opposite side of the ear lugs 31 and 32. 70 Each of the lugs is provided with a fit-up hole 33. The beveled edges 27 and 30 of the companion castings A and

D are curved along arcuate lines toward the bottom part of the two castings.

The bail ear E is preferably secured to the castings A and D by the method shown best in Figs. 3 and 12. The back casting D is provided with an integral flange 34 provided with a beveled edge portion 35 spaced from a beveled edge portion 36 of leg 37 of the ear E. Similarly, a leg portion 38 of the ear E is provided with a beveled edge 39 spaced from the beveled edge 40 of casting B. The B recesses thus formed are filled with welding metal 26.

The lip casting B is provided along its front side with a forwardly-extending ear lug 41 having a beveled front face 42 and a beveled rear face 43. Similarly, the front casting is provided adjacent the flange 41 with a flange 44 having a beveled face 45 at its front and a beveled edge 46 at its rear. The flanges 41 and 44 are provided with apertures through which extends a bolt 47. The V-recesses between the inclined faces described are filled with welding metal 26, as shown best in Fig. 7.

The back casting D may be provided with the usual pivot ears 48 and hinge ears 11, and a door F of any suitable construction may be employed.

In the completed dipper structure shown in Fig. 1, the welding metal 26 joining the castings A, B and C forms a substantially continuous curve extending downwardly from the top of casting B and to the bottom of casting A, with the curve extending inwardly at the top of the casting so as to increase the length of the lip casting B and downwardly in a direction toward the casting C to thus limit or diminish the length of casting C and thence rearwardly so as to increase the depth of the heel portion C'. The curved line of union thus compensates for the areas of greatest wear while at the same time providing a union which is effective against stresses in different directions. At the same time, the spaced ear lugs, by providing semicircular areas of welding metal, buttress the union against stresses from different directions. Similarly, the welding metal 26 extending between the castings A and D provide curved areas of union which greatly strengthen the union against stresses from different directions. Further, the line of union of the welding metal 26 between the bail ear E and the castings A and D follows arcuate or curved lines which take care of the angular stresses imposed upon the structure here. The ear lugs not only serve as a means for assembling the castings in the desired position for welding, but also provide arcuate lines of weld which strengthen the union. Further, the ear lugs may be used again when a part is worn and is to be replaced. For example, the lip B may be removed by burning a line along the weld line and a new lip may then be attached and butt-welded as described.

Operation

In the operation of the process and structure, the castings A to E, inclusive, are precast with beveled edges and with mating ear lugs. The castings may then be brought together, even by a single workman, and secured, and thereafter the workman can butt-weld the structure as indicated in the drawing to form an extremely strong unitary structure. By employing curved lines of weld and by interrupting lines of weld with spaced ear lugs which form arcuate weld segments, the structure is united for effective operation against all of the stresses to which a dipper is subjected. After the parts are brought together, bolts are placed through the fit-up holes and drawn to secure the parts in the desired relation for welding, and the welding is then accomplished. We prefer to employ electric automatic welding, but any suitable welding mechanism may be used. After the welds are complete, the bolts may be removed.

With the structure shown, it will be noted that the main portion of the front casting C is of small area, while the wearable portion, namely, the heel, extends

the farthest distance from the arcuate weld line 23. At the same time, the lip casting B has a large area and considerable wear can take place before reaching the weld lines. The arcuate weld line, therefore, connecting the

lip casting B, front casting C, and each side casting A, is not only effective in providing a strong resistance to torsional stresses from different directions, but also provides a structure in which the highly wearable portions are given the greatest area for wear before reaching the weld line.

While in the foregoing specification the lip B and front C are separate parts connected by butt-weld so that the lip may be burned off the dipper through the butt-welds and replaced by butt-welding, our invention 15 contemplates also the production of dippers with a lip and front as a one-piece integral part, constructed as shown in the drawings but with the butt-weld between the lip and front omitted. With the structure as shown in the drawings, the old lip, when worn, may be burned off 20 through the butt-welding and a replaceable or new lip connected to the front by butt-welding, as heretofore described.

With the foregoing structure, the castings can be cast with relatively wide variation in parts because the butt-welding permits substantial variation, while at the same time the arcuate reinforcements placed throughout the dipper structure give the necessary strength. As a result, the dipper can be formed at much less expense and the parts united into a unitary structure of great strength 30 meeting the demands of a power shovel dipper, etc.

While, in the foregoing specification, we have set forth specific procedure and structure in considerable detail for the purpose of illustrating an embodiment of the invention, it will be understood that wide variation of 35 such details may be made by those skilled in the art without departing from the spirit of our invention.

We claim:

1. A dipper, comprising a cast front, lip, side and back, each casting having edge portions forming a continuous edge recess with a companion casting for forming a welding metal recess therebetween, ear lugs projecting laterally from each casting and overlapping mating ear lugs on the companion casting, each ear lug having its outer edge portion beveled to form a weld 40 recess between it and the adjacent portion of the companion casting, said lugs having alignable fit-up holes, bolts extending through said fit-up holes and aligning said lugs so that the castings are provided between them with a continuous recess for welding metal, said welding 45 metal recesses being provided on each side of the castings to provide continuous lines of weld and in which the weld line about the laterally-extending lugs on one side of the casting extends in the opposite direction from the arcuate weld line about the laterally-extending lugs at the opposite side of the casting, and welding metal in a continuous 50 line filling the weld recesses between the castings and about said laterally-extending lugs.

2. A dipper, comprising at least two castings having edge portions forming a continuous edge recess with a companion casting for receiving welding metal therebetween and on each side of said castings, ear lugs projecting laterally from each casting and overlapping mating ear lugs on the companion casting, each ear lug having its outer edge spaced from the companion casting 55 to form a weld recess therebetween, said lugs having alignable fit-up holes adapted to receive bolts for uniting the castings and aligning them for receiving the welding metal, the weld recesses about the lugs on one side of the castings extending in the opposite direction to the weld 60 recesses about the lugs on the opposite side of the castings, and welding metal in a continuous line filling the weld recesses between the castings and about the laterally-extending lugs.

3. In a dipper having cast portions brought together 65 in edge-to-edge relation to form therebetween continuous

weld recesses, lugs carried by said adjacent castings and projecting laterally into overlapping relation, said lugs being apertured to receive bolts for uniting and aligning said castings, said lugs being spaced from the companion castings to provide therebetween weld recesses which communicate with the weld recesses between the castings, and welding metal in a continuous line filling the weld recesses between the castings and about the laterally-extending lugs, the weld portions about the laterally-extending lugs on one side of said castings extending in an opposite direction to the weld recesses about the lugs on the opposite side of the castings.

4. A dipper, comprising at least two adjacent castings having edge portions brought together to form therebetween a continuous curved welding metal recess merging at intervals with arcuate weld recesses, said arcuate weld recesses being formed by ear lugs carried by the companion castings and extending in overlapping relation, the ear lugs having their outer edge portion beveled

to form said arcuate recesses between them and the adjacent portion of the companion casting, said ear lugs being provided with fit-up holes adapted to receive bolts for aligning said lugs and said weld recesses, and welding metal in a continuous line filling the weld recesses between the castings and about said laterally-extending lugs.

5. The structure of claim 4 in which the weld recesses are provided on opposite sides of said castings and said arcuate weld recesses on the one side of said castings extend in opposite directions to the arcuate recesses on the opposite side of the castings.
